Application April 4, 1952, Serial No. 280,468

10 Claims. (Cl. 89—24)

This invention relates to guns and, more particularly, to improved breech operating mechanism and breech controlled firing mechanism for an automatic gun.

The illustrated gun is adapted to receive ammunition from an improved ramming mechanism which forms the subject-matter of an application of Charles J. Gross, Serial No. 280,498, filed on April 4, 1952, to which the ammunition is supplied by a loading mechanism forming the subject-matter of another application, that of C. W. Greene, Serial No. 280,524, filed on April 4, 1952.

In guns having the sliding wedge type of breech mechanism, of which the present gun is an example, a part of the opening movement of the breechblock is utilized to operate extractors to eject an empty shell case from the gun. This operation causes the operating mechanism for the breechblock to be relatively heavily loaded at or near the end of its breech opening movement. Again, at the beginning of the opening movement of the breechblock, its operating mechanism is subjected to a relatively great load in overcoming the inertia of the breechblock and also the tendency caused by the firing pressure for it to become seated against its ways.

In view of the foregoing, one object of the invention is to provide an improved breech operating mechanism arranged to operate with a high mechanical advantage at both ends of its stroke, corresponding to the times when the opening movement of the breechblock begins, and when the extractors are operated, toward the end of the movement of the breechblock away from its closed position.

To this end, and in accordance with one feature of the invention, the illustrated breech mechanism comprises, with a crank shaft, a pair of fixed cams which cooperate with the crank shaft during recoil movement of the gun to impart an opening movement to the breechblock, one of the cams and the crank shaft being arranged effectively to impart a movement of overtravel to the breechblock beyond its normal open position which is utilized to operate the extractors to eject the empty shell case from the gun. In the application of the present invention to the illustrated breech mechanism, one cam is arranged to cooperate with the crank shaft to the best advantage to initiate the opening movement of the breechblock. However, as this cam becomes more and more ineffectual, on account of its changing relation to the recoiling crank shaft, the other cam is designed to take over the operation of the crank shaft at the end of the opening movement of the breechblock.

Heretofore, breech mechanism has been designed to have a locking effect upon the breechblock when the latter is in its closed position, and ordinarily to the detriment of its effectiveness in driving the breechblock throughout its stroke. In the present construction, on the other hand, the breech operating mechanism is arranged with regard to the best possible driving characteristics, and is combined, in accordance with a further feature of the invention, with separate means for locking the breechblock in its closed position, this locking means being operated to

2

release the breechblock in response to recoiling movement of the gun and in advance of the time when the breech operating mechanism is actuated to open the breechblock. Furthermore, upon being released from the breechblock the locking means is held in its inoperative position by the breechblock, which later permits the locking means to move back into its locking position automatically upon the arrival of the breechblock in its closed position.

Invention is also to be recognized in the combination with the locking means of firing mechanism, the control and operation of which is also related to the opening and closing movements of the breechblock, as well as to the movements of the gun in recoil and counter-recoil. More specifically, in addition to having the usual firing pin arranged to slide from within the breechblock into engagement with the primer of a shell, the illustrated firing mechanism comprises connections associated with the above-mentioned locking means for operating the firing pin automatically when the breechblock has become locked in its closed position. These connections are also so constructed and arranged as to insure the retraction of the firing pin within the breechblock before its opening movement takes place.

These and other features of the invention will now be described in detail with reference to the accompanying drawings, and will be set forth in the claims.

In the drawings,

Fig. 1 is a plan view of the right-hand unit of a dual gun embodying the invention, together with a ramming mechanism and a part of a hoist for supplying ammunition to the gun;

Fig. 2 is a side elevation of the gun and ramming mechanism shown in Fig. 1 as viewed from the left;

Fig. 3 is a side elevation of the breech mechanism of the gun as viewed from the right;

Fig. 4 is a plan view of the breech mechanism when the gun is in battery;

Fig. 5 is a sectional plan view of the breech mechanism with the gun in battery; and

Figs. 6 and 7 are sectional plan views of the breech mechanism illustrating the breechblock in its open position, Fig. 7 illustrating a shell being projected into the chamber of the gun by the ramming mechanism.

Each unit of the illustrated gun (the right-hand unit only being shown in the drawings) comprises a slide 10 in which a tube 12 (Fig. 1) is mounted for recoil movement. Each slide has a trunnion 16 at each side, rotatably mounted in standards 18, 18 fixed to the gun carriage, permitting the gun to be swung in elevation. Associated with each unit of the gun is a hoist 20 which automatically supplies ammunition to a ramming mechanism 22 (of the type disclosed in the Gross application referred to above), the latter being arranged to transfer the rounds laterally of the gun from the hoist to the axis of the tube, and then to project the rounds into the chamber 24 (Fig. 7) of the tube axially thereof.

The illustrated gun comprises a breech mechanism of the sliding wedge type, and has a breech ring 26 (Figs. 5, 6 and 7), into which the tube is threaded, the ring having integral therewith opposed slides 28, 28 between which a breechblock 30 is mounted to reciprocate horizontally. Lugs 31, 32 fixed to the breech ring slide, when the gun recoils, in guideways formed in plates 33, 34 respectively, which are fixed upon the slide 10. Extractors 35 having lips 36 adapted to be engaged by the flange 37 on the shell casing are arranged to rock upon the end of the tube, in the usual manner, under the control of their lugs 38 which are received in arcuate slots 39 in the slides 28, and also in cam slots 40, 40 formed in the upper and lower sides of the breechblock.

As is well understood in this art, during the latter part of the movement of the breechblock 30 away from its

closed position, shoulders 42 at the rear sides of the cam slots engage the lugs 38 and cause the extractors to rock upon the tube, and to eject the empty shell case from the gun. The breechblock is locked in its open position by the engagement of another set of shoulders 44 (Figs. 4 and 7) at the forward sides of the cam slots with the lugs 38.

The lugs are connected to a buffer mechanism comprising levers 46, 46 one of which is pivoted upon each of the slides 28 and is connected at its upper end by a link 47 to the lug. The lower end of each lever 46 is pivoted to a spring plunger 48, arranged to slide in an hydraulic buffer cylinder 49 of usual construction and fixed to the breech ring.

Opening and closing movements of the breechblock are caused and controlled by the following mechanism. A shaft 50, rotatably mounted in bearings 52 on the breech ring, has a central crank arm 54 (Figs. 3, 6 and 7) upon which a block 56 is pivoted, the block being arranged to slide in a slot 58 formed in the breechblock. Pivoted at 59 upon the crank arm 54 is a yoke 60 to each side of which are fixed plungers 61 arranged to bear against compression springs (not shown) encased in tubes 62. A holder 64 for these tubes is carried by rods 65 and struts 66 which are fixed to the bearings 52. The crank arm 54 is thus urged in a clockwise direction, tending always to drive the breechblock toward its closed position.

As stated above, the breechblock is locked in its open position by the extractor lugs 38, but is released, when a round is inserted into the chamber, by the action of the round upon the lips 36 of the extractors which are rocked to move the lugs off the shoulders 44 of the cam slots 40. Firing is effected automatically by a sliding firing pin 67 which impinges upon the primer of the shell.

Mechanism operated by the recoil of the gun is provided for moving the breechblock to its open position. This mechanism comprises a cam plate 68 fixed to the plate 33, and having a cam opening 69 into which extends a crank 70 fixed to the upper end of the shaft 50. When the gun recoils from its battery position (Fig. 4), the crank 70, since it moves with the breech ring, moves rearwardly with the gun, but is not rotated, at first, because it runs along a straight portion 71 of the cam opening. The opening of the breechblock is thus delayed to permit retraction of the firing pin 67 into the breechblock, as will be described below.

Later, when the crank 70 moves onto an incline 72, the shaft 50 and crank arm 54 are rotated counterclockwise whereby the breechblock is moved away from its closed position against the pressure of the spring loaded plunger 61. At this time, the direction of the pressure between the incline and the crank 70 is approximately at a right angle to the arm of the crank 70, and an effectual driving relation exists between the cam and crank. However, near the end of the recoil movement, when the crank 70 reaches a shoulder 73 at the outer end of the incline, the direction of the pressure between the crank and the cam becomes so nearly parallel to the arm of the crank that only a small component of the pressure between the crank and the cam is effectual to turn the crank. Before this latter condition can take place, another crank 76 on the lower end of the shaft 50 cooperates with a second cam 78 in the plate 80 which is fixed to the plate 34 to operate the crank shaft. That is, when the crank 70 reaches the shoulder 73 the crank 76 will have been moved into contact with an incline 82 on the cam 80, the pressure between which and the crank 76 is directed nearly perpendicular to the arm of the crank 76, whereby an effective drive for the crankshaft is established. From this point in the recoil movement of the gun until the end of such movement has been reached, the crank 70 moves freely within a clearance opening 83 in the plate 68 without engaging it, the crankshaft at this time being under the control of the crank 76 which bears against the outer side of a restricted

opening 84 in the cam 80. It is during the period when the crank 76 approaches and passes the inner end of the incline 82 that a movement of overtravel of the breechblock beyond its open position is imparted to the breechblock, and the extractor lugs 38 are cammed forwardly of the gun by the shoulders 42 of the breechblock to impart a shell ejecting movement to the extractors.

After the crank 76 has fully entered the restricted opening 84 and the counter-recoil movement of the gun has begun, the crank engages a short incline 86 at the inner side of the opening 84 which, with the opposite portion of the incline 82, controls the reverse overtravel movement of the breechblock until it is returned to its open position where it is locked by the engagement of its shoulders 44 with the extractor lugs 38. The crank 76 now having passed off the incline 86, it runs freely along a straight surface 87 of the cam 78, without being driven thereby, during the remainder of the counter-recoil movement of the gun back to its battery position.

Since the firing of the illustrated gun depends upon the operation of the ramming mechanism, this mechanism will now be briefly described, but only so far as is necessary for an understanding of the operation of the breech mechanism. For a more complete description of the ramming mechanism reference may be made to the above-mentioned Gross application.

The rammer comprises one pair of arms 96, 96 (Fig. 2) and a second pair of arms 98, 98 upon the outer ends of which is mounted a frame 100 adapted to hold one shell. Immediately after a shell has been deposited into the frame from the hoist 20 these parts have the relation in which they are illustrated in Fig. 1, the pairs of arms 96, 98 extending lengthwise of the gun. A spring loaded plunger 101 arranged to slide in a housing 102 supplies the force for operating driving mechanism 103 for the arms 96, 98 which are swung in a counterclockwise direction to bring the rammer frame into such a position (Fig. 7) that the round is coaxial with the gun. As the rammer frame approaches this position, a double chain 104, having fingers 106 which grip the flange of the shell, is operated to project the round into the chamber of the gun. Just before the shell is seated in the chamber the flange of the shell engages the lips 36 of the extractors which, under the control of the buffer mechanism associated therewith, decelerate the ramming movement of the shell from a velocity of about 40 ft. per second to approximately 10 ft. per second. Before this movement of the extractors is completed the lugs 38 are moved from beneath the shoulders 44 on the breechblock permitting the latter to be closed. When the breechblock arrives at its closed position, it is automatically locked in this position and the shell is fired, as will be more fully described below.

When the gun recoils the plunger 101 is carried rearwardly to its energized position by the lug 31, which abuts a collar 108 fixed to the plunger, without having any effect upon the rammer frame because of the use of one-way clutch mechanism between these parts, and the plunger is temporarily held in its energized position by a latch 110. The latch is pivoted at 112 on the base of the ramming mechanism and is arranged to overlie a shoulder 114 formed upon the collar 108. This latch has an arm 116 to the end of which is connected the plunger of a solenoid 118, which, when it is energized by closing an electrical firing circuit (not shown), retracts the latch from the shoulder 114. A cycle of operation of the ramming mechanism is thus started, the shell therein immediately being swung away from the hoist to the axis of the gun, and then rammed into the gun. When the breechblock is closed the gun is automatically fired as will now be described.

The firing pin 67 (Figs. 5, 6 and 7) is mounted to slide in a bore 120 in the breechblock from a retracted position within the block, as illustrated in Figs. 6 and 7, into its firing position as illustrated in Fig. 5. It is thus

operated by a lever 122 to which the firing pin is pivoted at 124, the lever being mounted to swing in a slot 126 in the breechblock about a pin 128 which is fixed to the block. In each side of the lever 122 there is an elongated slot 129, these slots being arranged to receive a pair of pins 130, 130 which project toward each other from a bifurcated plunger 132 which is mounted to slide in the breech ring lengthwise of the gun. The plunger 132 is pivoted at 134 to one arm 136 of a lever having two other arms 138, 140, this lever being fixed to a shaft 142 which is rotatably mounted upon a bracket 144 fixed to the breech ring. A spring loaded plunger 146 is pivoted at 148 to the arm 138 and causes the firing pin to be urged toward its firing position through the connections just described.

When the breechblock is out of its closed position, the forward end of the plunger 132 abuts the rear surface of the breechblock, and the firing pin is held in its retracted position. When the breechblock moves toward its closed position, the lever 122 at first slides freely with respect to, and without being moved by, the pins 130. However, when the breechblock arrives at its fully closed position, a socket 149 formed in the block at each side of the slot 126 becomes aligned with the plunger 132 which then enters the socket, and causes the firing pin to impinge upon the primer of the shell in the gun. The gun is now fired and begins its recoil movement, but before any movement of the breechblock away from its closed position takes place, a crank pin 150 on the arm 140 engages a cam 152 which is fixed to the plate 80. The firing pin is thus moved into its retracted position as shown in Fig. 6. The slots 129 in the lever 122 now being parallel to the path of the breechblock, its opening movement imparts no movement to the firing pin, and the firing pin is held in its retracted position by engagement of the end of the plunger 132 with the rear surface of the breechblock throughout the remainder of the firing cycle until immediately before the gun is next fired.

The firing cycle of the gun and the operation of the breech mechanism will now be summarized. When at rest, the gun is in battery with the breech open as illustrated in Fig. 7. When the next round of ammunition is delivered into the gun chamber by the ramming mechanism, the extractors are engaged by the flange 37 on the shell case and are swung so as to move the lugs 38 away from the shoulders 44 of the breechblock, whereby the latter is permitted to slide into its closed position under the influence of the spring loaded operating shaft 50. This swinging movement of the extractors is snubbed by the buffer mechanism associated with them, in order to avoid excessive jolting of the shell as it becomes seated in the chamber of the gun. While the breechblock slides toward its closed position the pins 130 slide freely within the slots 129 in the lever 122 without operating it, and the firing pin 67 is held in its retracted position by the plunger 132 the forward end of which engages the breechblock. However, when the breechblock reaches its closed position, the plunger 132 slides into the socket 149 causing the breechblock to be locked in its closed position, the lever 122 to be swung forwardly, and the firing pin to be operated to fire the shell.

Upon being fired, the gun immediately recoils bringing the crank pin 150 into engagement with the cam 152, whereby the firing pin is again retracted within the breechblock. Later, the crank 70 moves onto the incline 72 of the cam plate 68 causing the breechblock to be moved to its open position. During the final portion of the recoil movement the crank 76 cooperates with the cam plate 80 to impart a movement of overtravel to the breechblock which is utilized to operate the extractors 35 to eject the empty shell case from the gun.

This movement of overtravel is reversed during, and in predetermined relation to, the initial counter-recoil movement of the gun. Upon being returned to its open

position, the breechblock is locked therein by the engagement of its shoulders 44 with the extractor lugs 38, but the gun returns to battery with a continuous counter-recoil movement, the breech remaining open until the next shell to be fired is rammed into the gun.

Having thus described my invention, what I claim as new and desire to secure by Letters Patent of the United States is:

1. In a breech mechanism for a gun having a breech-block mounted to slide between open and closed positions, operating mechanism for said breechblock comprising a crank shaft movable with the gun in recoil and counter-recoil, said shaft having a pair of angularly related crank arms, and a pair of fixed cams, one of said cams being constructed and arranged to cooperate with one of said crank arms during recoil movement of the gun to impart an opening movement to said breechblock, the other of said cams being constructed and arranged to cooperate with the other of said crank arms during the terminal portion of the recoil movement of the gun and during its initial counter-recoil movement positively to impart a movement of overtravel to said breechblock beyond and back to its open position.
2. In a breech mechanism for a gun having a slide in which a gun tube is mounted for recoil and counter-recoil movements, a breechblock associated with said tube and mounted to slide between open and closed positions, operating mechanism for said breechblock comprising a crank shaft mounted for movement with said tube, said shaft having a pair of angularly related crank arms, and a pair of cams fixed to said slide, each of said cams being associated with one of said crank arms, said cams being constructed and arranged to cooperate successively with said crank arms during recoil movement of the gun to move said breechblock into and beyond its open position and to return said breechblock to its open position during the initial counter-recoil movement of the gun tube.
3. In a breech mechanism for a gun having a slide in which a gun tube is mounted for recoil and counter-recoil movements, a breechblock associated with said tube and mounted to slide between open and closed positions, operating mechanism for said breechblock comprising a crank shaft operatively connected to said breechblock and mounted for movement with said tube, said shaft having a pair of angularly related cranks, and a pair of cams fixed to said slide, one cam being associated with each of said cranks, said cams being shaped so as to permit said breechblock to move freely between its said positions when said gun tube is in battery, one of said cams being constructed and arranged to cooperate with one of said cranks during the recoil movement of the gun to impart an opening movement to said breechblock, the other cam being constructed and arranged to cooperate with the other crank to impart a movement of overtravel to said breechblock beyond and then back to its open position during the terminal portion of the recoil movement and the initial counter-recoil movement of the gun, respectively.
4. In a breech mechanism for a gun having a breech-block mounted to slide between open and closed positions, operating mechanism for said breechblock comprising a crank shaft operatively connected to said breechblock and movable with the gun in recoil and counter-recoil, said crank shaft having a pair of angularly related cranks, yielding means acting upon said crank shaft to urge said breechblock toward its closed position, and a pair of fixed cams, one cam being associated with each of said cranks, one cam and the crank associated therewith being constructed and arranged to impart an opening movement to said breechblock, the other cam and crank being constructed and arranged positively to impart a movement of overtravel to said breechblock beyond and back to its open position.
5. In a breech mechanism for a gun having a breech-

block mounted to slide into and out of a closed position, mechanism for operating said breechblock comprising a cam and a shaft which is movable with the gun in recoil and counter-recoil and has a crank cooperating with said cam to move said breechblock into its open position in response to recoil movement of the gun, the combination of a second cam and a second crank on said shaft, said second cam and crank cooperating to impart a movement of overtravel to said breechblock beyond and back to its open position during the terminal portion of the recoil movement of the gun and its initial counter-recoil movement respectively, extractors, and connections between said extractors and said breechblock actuated by said breechblock during its movement of overtravel for operating said extractors to eject a shell from the gun.

6. In a breech mechanism for a gun having a breechblock mounted to slide into and out of a closed position, operating mechanism for said breechblock comprising a shaft movable with the gun in recoil and counter-recoil, said operating mechanism also comprising a fixed cam and a crank fixed to said shaft, said crank being operated by said cam in response to recoil movement of the gun to cause said breechblock to be moved into its open position, the combination of a second cam, a second crank fixed to said shaft and arranged to cooperate with said second cam to impart a movement of overtravel to said breechblock beyond its open position, extractors for ejecting a shell from the gun, and extractor cam surfaces upon said breechblock arranged to operate said extractors to eject the shell during the said movement of overtravel of said breechblock, said second cam and crank also being arranged to reverse the said movement of overtravel of said breechblock during the initial counter-recoil movement of the gun.

7. In a breech mechanism for a gun, a breechblock mounted for movement between open and closed positions, a firing pin mounted upon said breechblock for movement from within the breechblock into firing position, and mechanism for operating said firing pin comprising a spring loaded plunger cooperating with a shoulder on said breechblock to hold said firing pin retracted within said breechblock while said breechblock is out of its closed position, said plunger also being mounted for movement across said shoulder upon the arrival of said breechblock in its closed position whereby said firing pin is released for movement into its firing position.

8. In a breech mechanism for a gun having a breechblock mounted for movement between open and closed positions, said breechblock carrying a firing pin mounted

for movement from within it into a firing position, mechanism for operating said firing pin comprising a locking member biased toward said breechblock into engagement therewith to hold said firing pin retracted within said breechblock while it is out of its closed position, said breechblock having a shoulder across which said member is moved upon the arrival of said breechblock in its closed position whereby said breechblock is locked in its closed position and said firing pin is released for movement into its firing position in succession.

9. In a breech mechanism for a gun having a breechblock mounted to move between open and closed positions, a firing pin mounted upon said breechblock for movement between a retracted position within said breechblock and a firing position, mechanism for operating said firing pin comprising a locking member mounted for movement transversely of the path of said breechblock into yielding engagement therewith whereby said firing pin is retracted within said breechblock when it is away from its closed position, said breechblock having a socket for receiving said member when said breechblock is in its closed position whereby it is simultaneously locked in its closed position and said firing pin is released for movement into its firing position.

10. In a breech mechanism for a gun having a breech ring in which a breechblock is arranged to slide between an open and a closed position, a firing pin mounted upon said breechblock to slide from within said breechblock into a firing position in which it projects out of said breechblock, and means for operating said firing pin comprising a spring loaded plunger mounted to slide in the breech ring across the path of said breechblock into yielding engagement therewith, pin and slot connections between said plunger and said firing pin, said breechblock having a socket for receiving said plunger upon the arrival of said breechblock into its closed position, whereby it is simultaneously locked in its closed position and said firing pin is released for movement into its firing position.
